UNITED STATES PATENT OFFICE.

WILLIAM F. WARNER, OF DAVENPORT, IOWA.

INTERNAL-COMBUSTION ENGINE.

1,153,364.

Specification of Letters Patent. Patented Sept. 14, 1915.

Application filed December 22, 1912. Serial No. 868,056.

To all whom it may concern:

Be it known that I, WILLIAM F. WARNER, a citizen of the United States, residing at Davenport, in the county of Scott and State 5 of Iowa, have invented certain new and useful Improvements in Internal-Combustion Engines, of which the following is a specification.

My invention relates to equipments for 10 internal combustion engines.

One of the objects of my invention is to provide means whereby to automatically adjust the appurtenant devices and apparatus necessary for, and incident to the 15 per operation of an engine, to produce the best results when being started, by means that become operable when the speed of the engine has fallen below a predetermined velocity, as when the engine is being 20 stopped, and to automatically readjust said appurtenant devices, and apparatus, consistent with the best operation of the engine at a critical speed, at which constancy of operation is desired to be maintained, at or 25 before the time when such speed has been attained.

Other and further objects of my invention will become readily apparent to persons skilled in the art, from a consideration 30 of the following description when taken in conjunction with the drawings, wherein

Figure 1 is a side elevation of a fragment of a typical engine, showing the associated appurtenances. Fig. 2 is a side elevation, 35 viewing the other side. Fig. 3 is an end view of the engine. Fig. 4 is a section taken on line 4-4 of Fig. 2. Fig. 5 is a vertical, central section taken through the carbureter, and Fig. 6 is a vertical section 40 taken through a supplementary fuel container and alarm initiating device.

In all the views the same reference characters are employed to indicate similar parts.

45 In the exemplification which I have chosen for the purpose of illustrating my invention, 10 is a typical engine of the internal combustion type, shown in driving relation with a dynamo 11 by means of a 50 chain or belt 12.

13 is a speed responsive governor, and 14 is a carbureter of typical type.

A fuel reservoir 15 contained in the base 55 of the engine is connected to a supplementary reservoir 16 by a pipe 17.

17 is a fuel pump operated from a crank arm 18 by a rod 19. The crank arm 18 is connected to a valve operating rocker arm 20. The pump 17 is connected with the carbureter 14 by means of a pipe 21 and an 60 overflow pipe 22 is connected with a receptacle 23 that has connection, by pipe 24, to the supplementary reservoir 16. By means of the pump the fuel is maintained in the carbureter at constant level for the proper 65 operation thereof.

The engine is provided with an outwardly seating compression relief valve normally held closed by the spring 24, as when said spring is not dominated by other influences. 70 A spark-time-controlling mechanism 25, comprises a rotatable part 26 rotated by the shaft 27 in time relation with the movement of the piston, and a relatively oscillatable part 28 capable of oscillation by means of the rod 29. The oscillation of the part 28, with reference to the rotatable part 26, varies the time that the spark is made in the cylinder with reference to the power or compression stroke of the piston. 75

80 The carbureter 14 is provided with a laterally projecting air chamber 30 containing an electro-thermic air heating coil 31. This coil is adapted to be contained in an electric circuit and to be heated by the current thereof, so as to warm or heat the air that passes into the carbureter at the time when the engine is cold and is about to be started.

85 A switch 32, comprising a blade 33 pivoted, as at 34, to a standard 35, is adapted to short circuit the air heating coil 31, when the movable blade 33 makes contact with the blade 36. 90

95 Wire 37 is connected to wire 38, the latter being connected to the blade 35 of the switch and also connected to one end of the heating coil 31, the other end of the heating coil being connected to an insulating block 31' secured to a part of the carbureter. Wire 39 is supported by said block and connected to the terminal 37' of the coil 31, as by a bolt 39'. A wire 40 is connected to the blade 36 of the switch and to a suitable source of electric current supply. When the switch 32 is closed the air heating coil 31 is short circuited by the wire 38, and blade 33, the current coming in on the wire 37, passing over the wire 38, through the pivoted switch blade 33, to the other lead wire 40, thereby short circuiting the heating coil. The piv- 100
105
110

oted switch blade 33 is connected to a pivoted lever 41 which is pivoted to a standard 42, as at 43, the other end of the lever 41 being connected to a lever 44, as at 45. The 5 lever 44 is fixed to a shaft 46, as at 47. The shaft 46 is adapted to be rocked on its bearings 48 and 49 by means of the speed responsive fly ball governor 13. The shaft 46 is normally held, in the position shown in 10 Fig. 3, by means of a spring 50 secured to a fixed part of the engine and to an arm 51 that is fixed to the shaft 46, as at 52. The speed responsive governor comprises weighted arms 54 and 55, pivoted as at 56 and 57 15 respectively, and having extended angularly disposed arms 58 and 59, respectively. A push rod 60 has bearings in the yoke piece 61, which is secured to the power wheel 62 carried on the engine power shaft 63.

20 Secured to the rock shaft 46 is a laterally and vertically extending arm 64 which normally bears against the push pin 60. When the arm 64 is moved to the left,—viewing Fig. 3,—as when the fly balls 54 and 55 of 25 the governor push the pin 60 outwardly the shaft 46 is thereby oscillated upon its bearings and the lever 44 is raised, the remote end of the lever 41 is depressed and thereby the switch 32 is closed.

30 Secured to the lever 44 is a vertically extending rod 65 carrying upon its upper end an adjustable cross piece 66. This cross piece bears upon the stem of the compression relief valve and when the lever 44 is 35 in the position shown in Fig. 3, the spring 50 being stronger than the spring 24 of the relief valve the latter spring is compressed and the relief valve opens so that when the engine is being started, as when it is initially 40 operated by the electric motor 11, there is a minimum of compression to be overcome in the cylinder of the engine, by reason of the action of the relief valve.

The auxiliary fuel reservoir 16 contains a 45 float 67 having a vertically extending stem 68 that passes freely through the top 69 and carries upon its upper end an adjustable metallic disk 70. The height of the disk from the top is a visual indication of the 50 supply of liquid fuel 71 that may be contained within the reservoir. When the supply becomes low, or about exhausted, the float 67 follows the liquid level down in the reservoir until the disk 70, carried by the 55 stem 68, makes electrical connection with circuit terminals 71 and 72, thereby closing an electric circuit containing an alarm bell 73 and a battery 74 over the wires 75 and 76. The bell is preferably located at some 60 point remote from the plant and serves as a means for warning the attendant that the engine fuel is about exhausted.

78 is a reservoir for lubricating oil for lubricating various parts of the engine, the 65 valve of which is normally closed but

opened by an energized electromagnet or solenoid 79.

In the operation of the device the parts of the engine and those of the appurtenant devices are normally in the positions shown 70 in the drawings. Now when the electric motor 11, which may subsequently become an electric generator to be driven by the engine, is energized for the purpose of initially starting the engine, and operating it until 75 it becomes self propelling, the switch 32 is open and the current that may pass through the motor will also pass through the switch into the heating coil 31, thus heating the air 80 that may be drawn into the carburetor 14 and thereby facilitating the admixture of the air and the hydro-carbon fuel such as gasoline or gas that may be taken into the cylinder to be subsequently compressed and ignited to provide the necessary power impulse to be effected by the engine.

The lever 44 is depressed, by operation of the spring 50, and therefore the vertical rod 65 carrying the cross piece 66 is in its lowest position and the stem of the compression relief valve is pushed downwardly against the spring 24, thereby reducing the compression in the cylinder of the engine and rendering the engine more easily to be started, and the rod 29, which is pivotally 95 connected to the pivoted lever 41, shifts the spark time device so that the spark will be made within the cylinder to ignite the charge at a time delayed, with reference to the reciprocation of the piston, beyond that 100 at which it would occur when the engine is running at its normal speed, and the electromagnet 75 is energized by the current that is used to energize the electric motor so that the lubricating oil may be distributed to the 105 necessary moving parts of the engine for the purpose of lubrication and these parts will remain in the condition described until the engine becomes self propelling, or until its shaft has attained a predetermined 110 speed, at which time the fly balls 54 and 55, of the speed responsive governor, will fly outwardly and cause the push pin 60 to be moved outwardly and to laterally move the vertical arm 64, which is connected to the 115 shaft 46, thereby raising the pivoted lever 44 and causing the relief valve to close, and raising one end of the pivoted lever 41, causing shifting of the spark time mechanism to a position consistent with the higher 120 speed of the engine, and closing the switch 32, thereby shutting the electric current out of the air heating coil 31, as now it will no longer be required, and the engine is conditioned, automatically, by the described 125 operations affecting the various devices and appurtenances, to run at a higher than starting or normal speed.

When the engine is being shut down or stopped, the spring 50 will cause the push 130

pin 60 to be returned to its normal position and the fly balls 54 and 55, of the governor, will assume the positions in which they are shown in the various figures, and 5 all of the apparatus will be automatically returned to the positions shown in the drawings, which they occupy when the engine is not in active operation. It will therefore be seen that all of the appurtenant 10 devices necessary for co-operative association with the engine, are automatically adjusted to meet the conditions for the best operation of the engine so that the engine may be started by the electric motor with the 15 least resistance and at the highest efficiency, and so as to meet the changed conditions of the engine, after it has become self propelling, necessary for its efficient operation at a higher or normal speed.

20 While I have herein disclosed a representation of the embodiment of my invention, it is evident that changes may be made in the arrangement and disposition of the parts, within the scope of the appended 25 claims, without departing from the spirit of my invention.

Having described my invention, what I claim is:—

1. An engine equipment for internal combustion engines, comprising, in combination, 30 air heating means, and a movable part controlling the same; spark time-varying means, and a movable part controlling the same; a speed responsive means, operated by the speed of the engine and having a 35 movable part; the first two said movable parts connected with the third said movable part for control thereby to vary the conditions of the air heating means and the spark 40 time-varying means in accordance with the speed of the engine, whereby the said air heating means and spark time-varying means may automatically be controlled for

efficient operation of the engine at different speeds of the engine. 45

2. An engine equipment for internal combustion engines, comprising, in combination, compression reducing means, and a movable part controlling the same; air heating means and a movable part controlling the same; 50 spark time-varying means, and a movable part controlling the same; a speed-responsive means, operated by the speed of the engine and having a movable part; the first three said movable parts connected with the 55 fourth said movable part for control thereby to vary the conditions of the compression reducing means, air heating means and a spark time-varying means in accordance with the speed of the engine whereby said 60 compression reducing means, said air heating means and said spark time-varying means may automatically be controlled for efficient operation of the engine at different 65 speeds of the engine.

3. An engine equipment for internal combustion engines, comprising, in combination, air heating means, and a movable part controlling the same; spark time-varying means, and a movable part controlling the 70 same; said devices normally conditioned for efficient starting of the engine; a speed responsive means, operated by the speed of the engine, and having a movable part; the first two said movable parts connected to 75 the third said movable part and automatically operable thereby at a predetermined speed of the engine to control said devices for efficient continued operation of the engine at and above said predetermined speed. 80

In testimony whereof I hereunto set my hand in the presence of two witnesses.

WILLIAM F. WARNER.
